UNITED STATES PATENT OFFICE.

ANDREW B. CLAYTON, OF UNION, NEW JERSEY, ASSIGNOR TO THE SINGER MANUFACTURING COMPANY, OF ELIZABETH, NEW JERSEY, A CORPORATION OF NEW JERSEY.

LOOPER-ACTUATING MECHANISM FOR SEWING MACHINES.

Application filed February 21, 1922. Serial No. 538,208.

To all whom it may concern:

Be it known that I, ANDREW B. CLAYTON, a citizen of the United States, residing at Union, in the county of Union and State of New Jersey, have invented certain new and useful Improvements in Looper-Actuating Mechanisms for Sewing Machines, of which the following is a specification, reference being had therein to the accompanying drawings.

This invention relates to improvements in looper mechanisms for sewing machines and particularly for chain-stitch sewing machines in which endwise and sidewise movements are imparted to a looper for cooperation with a reciprocating needle in the formation of chain-strokes.

The invention has for its object to improve the actuating mechanism for the loopers of chain-stitch sewing machines, whereby the operative path of movement of the loopers in completely assembled machines may be readily adjusted with respect to the needles to meet the various conditions of operations arising in commercial use of these machines.

To attain the object of the invention, the looper-carrier is adjustably secured upon a reciprocatory-oscillatory support operatively connected with independent actuating elements. The actuating element for imparting endwise movements to the looper comprises an eccentric, adjustably secured upon a rotary shaft and embraced by a split-strap clamped upon the eccentric by means of a screw-bolt affording a fulcrum-pin for pivotally sustaining a pitman reciprocated by the eccentric and operatively connected with the looper-carrier. The sidewise movements of the looper are permitted by this pivotal support of the pitman and are derived from an inclined crank, carried by the actuating shaft and embraced by the sleeved portion of a gyratory arm having a universal joint connection with a sleeve mounted upon the looper-carrier support to reciprocate the latter endwise but capable of oscillatory movements thereupon. This construction permits adjustment of the relative timing of the

eccentric and inclined crank whereby the path of movement of the looper may be readily altered. Further, the operative connections permit adjustment of the position of the looper which, together with the timing adjustments, readily enable an operator to accurately obtain the path of movement of the looper necessary to meet the particular operating condition.

In the accompanying drawings, Fig. 1 is a front view in elevation of a portion of the sewing machine embodying the present improved looper-actuating mechanism. Fig. 2 is a top plan view of the looper-actuating mechanism. Fig. 3 is a view substantially on the line $x-x$ of Fig. 1. Fig. 4 is a view substantially on the line $y-y$ of Fig. 2. Fig. 5 is a detail view of the inclined crank for imparting sidewise movements to the looper, together with the gyratory arm actuated thereby. Fig. 6 is a detail sectional view of the adjustable eccentric for imparting endwise movements to the looper, and Fig. 7 is a detail view of the looper-carrier support.

Referring to the drawings, the sewing machine, of which only a portion is shown, comprises a base 1 and an overhanging arm terminating in a head 2. Journaled for reciprocatory movements in the head 2 is the needle-bar 3 to which is suitably secured the needle-clamp bracket 4 carrying one or more needles, as 5. Also journaled for reciprocatory movements in the head 2 is the presser-bar 6 carrying the presser-foot 7 opposed to the feed-dog 8 operating through suitable feed-slots, as 9, provided in the throat-plate 10 and actuated in any well-known manner to carry the work past the needles.

Journaled in suitable bearings provided in lugs, as 11, on the base 1 is the rotary actuating shaft 12. Adjustably secured upon the shaft 12 by means of set-screws, as 13, is an eccentric 14, embraced by a split-strap 15 having apertured ears, as 15', projecting therefrom. Straddling the strap 15 is a yoke 16 of a pitman 17 and threaded into the lower arm of the yoke 16 and secured there-

upon by means of a nut 18 is a screw-bolt 19 of which the headed end rests upon the upper arm of the yoke and which bolt passes through said apertured ears 15'. By manipulation of the nut 18, the split-strap 15 may be caused to closely embrace the eccentric 14, and consequently wear between the eccentric and its embracing strap may be readily taken up. The screw-bolt 19, by means of the described construction, serves as a fulcrum-pin affording a pivotal support for the pitman 17 upon the strap 15, whereby lateral movement of the pitman is permitted.

The opposite end of the pitman 17 has a ball-and-socket connection with a bolt 20 adjustably secured by means of a nut 21 in an elongated slot 22 provided in an arm 23 projecting laterally from a reciprocating-oscillatory looper-carrier support 24. The looper-carrier support 24 is in the form of a tubular sleeve sustained for sliding and oscillatory movements upon a rod 25 suitably secured in apertures provided in the lugs 11 on the machine base. Secured upon the looper-carrier support 24 by screws, as 26, is a clamp 27 having a bracket-portion 28 in which is provided a grooved seat 29. Secured upon the seat 29, by means of a screw 30, is the shank of a looper-carrier 31 upon which are suitably fixed the loopers 32 adapted to cooperate in the usual manner with the needles 5 in the formation of chainstitches. It will be apparent that, by reason of the described connections, rotation of the eccentric 14 will impart reciprocating movements to the pitman 17, which in turn imparts oscillatory movements to the looper-carrier support 24 to transmit to the loopers their endwise movements.

In order to permit lubrication of the outer surface of the actuating eccentric 14 the flanged end 33 thereof, into which the securing set-screws 13 are threaded, is provided with a radial aperture 34 normally held closed by a ball 35 acted upon by a spring 36. The aperture 34 communicates with a plurality of reservoirs 37 provided within the eccentric and from which reservoirs the lubricant is conducted to the outer surface of the eccentric, by means of passages, as 38. Lubricating means is also provided for the bearing surface of the fulcrum-pin 19 which is formed with an aperture 39 extending longitudinally thereof permitting insertion of the lubricant, which is conducted to the outer surface of the fulcrum-pin through a plurality of transverse passages, as 40.

Sidewise movements are imparted to the looper by means of an inclined crank 41 adjustably secured upon the rotary-shaft 12 by means of the set-screws 42, which are threaded into a circumferentially disposed rib 43 intermediate the ends of the crank. Embracing the crank 41 upon opposite sides

of the rib 43 is the sleeved portion of a gyratory arm 44. Said sleeved portion comprises spaced members 45 having semi-spherical surfaces 46 complementary to similar surfaces 47 provided on caps, as 48, individually secured in position upon the members 45 by means of screws, as 49. As will be apparent, the rib 43 serves to prevent movement of the gyratory arm in the direction of the axis of the crank, while the arm itself may be readily detached from the crank by removal of the caps 48. At its lower end the arm 44 has ball-and-socket connections with a lateral arm 50 projecting from a sleeve 51. The sleeve 51 is journaled for oscillatory movements upon the looper-carrier support 24, being held against endwise movements thereupon by the hub of the arm 23 and by a split cap 52 threaded upon the end of the support 24 and held in position by means of a collar 53 clamped upon the cap 52.

Upon rotation of the inclined crank 41 gyratory movements are imparted to the arm 44 one component of which is taken up by the idle oscillation of the sleeve 51 upon the looper-carrier support. The other component of movement of the arm 44 imparts to the support 24 endwise movements upon the rod 25, whereby sidewise movements are transmitted to the looper or loopers. By circular adjustment of the eccentric 14 or of the inclined crank 41 upon the shaft 12, i. e., changing their timing with respect to each other the path of movement of the loopers may be appreciably altered to meet different requirements. It will be observed from the dotted lines in Fig. 2 that the center line of movement of the loopers in the position of the parts as shown is inclined to the direction of feed. The adjustments provided in the operative connections permit of correctly setting and operating the loopers without requiring the extreme accuracy in manufacture essential in prior constructions.

Having thus set forth the nature of the invention, what I claim herein is—

1. In a sewing machine, the combination with a main-shaft, a reciprocating needle, and a looper, of a rotary eccentric and a rotary inclined crank deriving their operative movements from said main-shaft for actuating said looper for cooperation with said needle in the formation of stitches, operating connections between the looper and said eccentric for imparting endwise stitch-forming movements to said looper, and operative connections between the inclined crank and the looper for imparting sidewise movements thereto.

2. In a sewing machine, the combination with a main-shaft, a reciprocating needle, and an endwise and sidewise movable looper adapted to cooperate with said needle in the formation of stitches, of actuating ele-

ments for said looper comprising a rotary eccentric and a rotary inclined crank deriving their operative movements from said main-shaft, operative connections between 5 the looper and said eccentric and inclined crank for imparting the endwise and sidewise stitch-forming movements to the looper, and means permitting adjustment of the relative timing of said eccentric and 10 crank.

3. In a sewing machine, the combination with a reciprocating needle, and an endwise and sidewise movable looper adapted to cooperate with said needle in the formation 15 of stitches, and a rotary actuating shaft, of actuating elements for said looper comprising a rotary eccentric and a rotary inclined crank carried by said shaft, means permitting adjustment of said crank upon 20 said shaft to vary the timing thereof with respect to said eccentric, and operative connections between the looper and said eccentric and inclined crank for imparting the endwise and sidewise movements to the looper.

25 4. In a sewing machine, in combination, a main-shaft, a reciprocating needle, a looper cooperating with said needle in the formation of stitches, a looper-carrier, a rotary eccentric deriving its operative movements 30 from said main-shaft, operative connections between said eccentric and the looper-carrier for imparting endwise movements to the looper, a rotary inclined crank deriving its operative movements from said main-shaft, 35 and a universal-joint connection between said crank and the looper-carrier for imparting sidewise movements to the looper.

5. In a sewing machine, in combination, 40 a reciprocating needle, an endwise and sidewise movable looper cooperating with said needle in the formation of stitches, a looper-carrier, means for imparting the sidewise movements to said looper, and means for imparting the endwise movements to the looper including a rotary actuating shaft, an eccentric carried by said shaft, a strap embracing said eccentric, a pitman pivotally connected with said strap to permit of lateral swinging movements of said pitman 45 relatively to said strap, and an operative connection between the pitman and said looper-carrier.

55 6. In a sewing machine, in combination, a main-shaft, a reciprocating needle, a looper cooperating with said needle in the formation of stitches, a looper-carrier, a rotary eccentric deriving its operative movements from said main-shaft, a strap embracing said eccentric, a pitman connecting said strap and the looper-carrier for imparting endwise stitch-forming movements to the looper, a pivotal support for said pitman permitting lateral movement thereof, a rotary inclined crank deriving its operative movements from said main-shaft, and

a universal-joint connection between said inclined crank and the looper-carrier for imparting sidewise movements to the looper.

7. In a sewing machine, the combination with a main-shaft, a reciprocating needle, a looper cooperating with said needle in the formation of stitches, a looper-carrier, and a reciprocatory-oscillatory support sustaining said looper-carrier, of means for imparting oscillatory movements to said support 75 comprising a rotary eccentric deriving operative movements from said main-shaft, a strap embracing said eccentric, and a pitman pivotally supported by said strap operatively connected with said support, and means for 80 imparting reciprocatory movements to said support comprising a rotary inclined crank deriving operative movements from said main-shaft, a sleeve mounted for oscillatory movements upon said support, and a universal-joint connection between said crank and said sleeve.

8. In a sewing machine, in combination, a reciprocating needle, a looper cooperating with said needle in the formation of stitches, 90 a looper-carrier, a reciprocatory-oscillatory support sustaining said looper-carrier, a rotary shaft, an eccentric adjustably secured upon said shaft, a strap embracing said eccentric, a pitman pivotally supported 95 by said strap and operatively connected with said support for imparting oscillatory movements to the latter, an inclined crank carried by said shaft, a sleeve mounted for oscillatory movements upon said support, and 100 a universal-joint connection between said crank and said sleeve.

9. In a sewing machine, in combination, a reciprocating needle, an endwise and sidewise movable looper adapted to cooperate 105 with said needle in the formation of stitches, a looper-carrier, a rotary shaft, an eccentric carried by said shaft, a strap embracing said eccentric, a pitman having a yoke straddling said strap, a fulcrum-pin pivotally securing 110 said yoke upon said strap, an operative connection between said pitman and said looper-carrier for imparting one of said movements to said looper, and means for imparting the other of said movements to said 115 looper.

10. In a sewing machine, the combination with a reciprocating needle, and a looper cooperating with said needle in the formation of stitches, of means for actuating said looper including a rotary shaft, an eccentric carried by said shaft, a split strap embracing said eccentric, a fulcrum-pin affording means for clamping the strap upon said eccentric, a pitman pivotally sustained upon 120 said strap by said fulcrum-pin, and operative connections between said pitman and the looper for imparting movements thereto.

11. In a sewing machine, the combination with a reciprocating needle, and a looper co- 130

operating with said needle in the formation of stitches, of means for actuating said looper including a rotary shaft, an inclined crank carried by said shaft having a circumferentially disposed rib intermediate its ends, a gyratory arm having split-sleeve sections secured upon said crank upon opposite sides of its circumferentially disposed rib, and operative connections between said arm and the looper for imparting movements to the latter.

In testimony whereof, I have signed my name to this specification.

ANDREW B. CLAYTON.
